[57] CLAIM

The ornamental design for a telephone stand or similar article, substantially as shown and described.

DESCRIPTION

FIG. 1 is a top front perspective view of a telephone stand showing our new design;

FIG. 2 is a front elevation thereof;

FIG. 3 is a top plan view thereof;

FIG. 4 is a right side elevation thereof, the opposite side is a mirror image of the side shown;

FIG. 5 is a bottom plan view thereof;

FIG. 6 is a top front perspective view of a modified embodiment of the telephone stand illustrated in FIG. 1;

FIG. 7 is a front elevation thereof;

FIG. 8 is a rear elevation thereof;

FIG. 9 is a top plan view thereof;

FIG. 10 is a right side elevation thereof, the opposite side is a mirror image of the side shown; and

FIG. 11 is a bottom plan view thereof.
